UNITED STATES PATENT OFFICE.

HERBERT E. VAN DORN, OF CHICAGO, ILLINOIS.

DRAWBAR CONSTRUCTION.

Application filed December 17, 1921. Serial No. 523,015.

To all whom it may concern:

Be it known that I, HERBERT E. VAN DORN, a citizen of the United States, residing at Chicago, county of Cook, State of Illinois, have invented a certain new and useful Improvement in Drawbar Constructions, and declare the following to be a full, clear, and exact description of the same, such as will enable others skilled in the art 10 to which it pertains to make and use the same, reference being had to the accompanying drawings, which form a part of this specification.

The present invention has for its object 15 to produce a novel drawbar construction for railway cars which will permit the coupler head to oscillate about a longitudinal axis without employing any elements which will detract from the simplicity, ruggedness and 20 durability highly desirable in structures of this kind and without making it necessary to select any particular form of attachment between the rear end of a drawbar and a car.

Viewed in another of its aspects my invention may be said to have for its object 25 to produce a simple, novel and sturdy drawbar construction which will permit the coupler head to move longitudinally in the usual way, swing in a vertical plane and oscillate about a longitudinal axis.

The various features of novelty whereby 30 my invention is characterized will herein-after be pointed out with particularity in the claims; but, for a full understanding of my invention and of its objects and advantages, reference may be had to the following detailed description taken in connection with the accompanying drawings, wherein:

40 Figure 1 is a side elevation of a drawbar arranged in accordance with the present invention, the coupler head being shown in dotted lines;

45 Fig. 2 is a vertical longitudinal section on an enlarged scale through the front end of the drawbar and coupler stem;

Fig. 3 is a section taken approximately on line 3-3 of Fig. 2;

50 Fig. 4 is a bottom plan view of that portion of the drawbar shown in Fig. 2;

55 Fig. 5 is a side elevation of the coupler stem disconnected from the drawbar but having its locking and holding ring in position thereon;

Fig. 6 is a view of the locking ring detached from the coupler stem, the parts thereof being fastened together; and

Fig. 7 is a front view of the drawbar, that is a view taken approximately on line 7-7 of Fig. 1 with the coupler stem omitted.

Referring to the drawing, 1 represents a drawbar shank of any usual or suitable construction, which may be connected at its rear end to a suitable spring draft rigging 2 by means of a vertical bolt or pin 3, whereby the drawbar is permitted to swing bodily about a vertical axis passing through the rear end thereof. The front end of the drawbar is adapted to be supported upon a suitable arc-shaped bar or track 4; there being a saddle 5 hung upon this track or bar so as to be slidable along the same. The saddle, as best shown in Fig. 7, has downwardly-projecting side flanges 6 each of which is provided at its lower edge with an inwardly-directed ledge 7. At the front end of the drawbar is a long flat nose 8 which rests loosely upon the ledges 7 so as to permit the drawbar as a whole to move back and forth in the longitudinal direction 80 relatively to the saddle. Just below and in rear of the supporting nose of the drawbar is a hollow cylinder 9 arranged with its axis extending in the longitudinal direction; the cylinder being open at both ends. 85

The stem for supporting the coupler head is in the form of a hollow cylinder or tube 10 fitting within the cylinder 9; the stem being enlarged at the front end so as to provide a rearwardly-facing shoulder 11 which 90 will bear against the front end of the cylinder 9 and limit the inward movement of the stem into the surrounding cylinder. The rear end of the stem projects somewhat beyond the supporting cylinder and is provided with an annular groove 12 the forward bounding wall of which lies in approximately the same vertical plane as the rear end of the cylinder 9 when the parts are assembled so that the shoulder 11 engages with the front end of that cylinder. 95

In order to hold the coupler stem securely against withdrawal when a pull is exerted upon the drawbar, I have provided a locking device in the form of a divided ring made of two parts 13 and 14 which, when placed together, will fit into the groove 12 and project therefrom far enough to engage 105

with the rear vertical face or end of the cylinder 9. The two members of the ring may conveniently be held together by providing them with registering ears 15 and 16, through which pass fastening bolts 17. It will be seen that when a pull is exerted on the coupler, the stresses are transmitted to the drawbar through the locking ring which presents a large section that must be sheared before the stem can be pulled out.

While the coupler stem is securely held against being pulled out or pushed back through the supporting bearing on the drawbar, it may freely rotate in said bearing about its own axis. In order to limit the extent to which the coupler stem may rotate, I have provided the drawbar with a pair of limiting plugs 18 and 19 projecting forwardly from the lower side of the cylindrical member 9, at the lower end of the latter, and spaced apart from each other transversely of the drawbar. On the stem 10 is a rib or lug 20 which lies between the lugs 18 and 19 and, by engaging with one or the other of these lugs as the stem is oscillated, serving to limit the oscillatory movements of the stem.

At the front end of the coupler stem are two separated forwardly-extending wings 21 and 22 between which any suitable coupler head may be placed and held so as to have freedom of vertical swinging movements by means of a suitable pin, not shown, passing through registering openings 23 in these wings. It is desirable to support the coupler head yieldingly in a predetermined normal position so that its downward swinging movements below that position will be against the tension of the springs 24 which normally hold the head up. To this end I have placed within the coupler stem, just behind the wings 21 and 22, a vertical, vertically-movable plunger 24 having on its lower end a flange 25 on which rests a compression spring 26 whose upper end bears against the top wall of the chamber 27 in which the spring and plunger are located. The lower end of the chamber is closed by means of a suitable detachable plate 28 through which the head 29 constituting that part of the plunger below the flange 25 projects. The head of the plunger rests upon the rear end of a lever 30 which is pivotally supported between its ends between ears 31 extending downwardly from the wings 21 and 22, by means of a suitable bolt 32 passing through said ears and through the lever. The front end of the lever projects forwardly far enough to lie underneath and support a coupler head such, for example, as shown in dotted lines at 33 in Fig. 1.

I claim:

1. In combination, a draw bar having at its front end a housing in the form of an

elongated cylindrical sleeve, a cylindrical stem extending through and rotatably fitted in said sleeve, means at the front end of said stem for supporting a coupler head, and shoulders on said stem in engagement with the opposite ends of the sleeve to hold the stem against lengthwise movement.

2. In combination, a draw bar terminating at the front end in a housing having the form of an elongated cylindrical sleeve, a cylindrical stem extending through said sleeve and rotatably fitted therein, means at the front end of said stem for supporting a coupler head, shoulders on said stem beyond the front and rear ends of said sleeve to hold the stem against lengthwise movement, one of said shoulders being detachable.

3. In combination, a draw bar terminating at the front end in a housing having the form of an elongated cylindrical sleeve, a stem extending through and rotatably fitted in said sleeve, means on the front end of the stem for supporting a coupler head, shoulders on the stem beyond the front and rear ends of said sleeve to hold the stem against lengthwise movement, said sleeve having on the extreme thereof lugs spaced apart angularly of the sleeve, and a part on said stem lying between said lugs and adapted to be engaged thereby at the end of a limited angular movement of said stem.

4. A drawbar having at the front end a cylindrical sleeve arranged with its axis extending longitudinally and open at the ends, a stem fitting rotatably in said sleeve and having a shoulder adapted to engage with the front end of the sleeve to limit the rearward movement of the stem, means at the front end of the stem for supporting a coupler head, said stem having an annular groove therein beyond the rear end of the sleeve, and a retaining ring fixed into said groove and projecting out of the same far enough to engage with the rear end of the sleeve to prevent the withdrawal of the stem in the forward direction.

5. A drawbar having at the front end a cylindrical sleeve arranged with its axis extending longitudinally and open at the ends, a stem fitting rotatably in said sleeve and having a shoulder adapted to engage with the front end of the sleeve to limit the rearward movement of the stem, means at the front end of the stem for supporting a coupler head, said stem having an annular groove therein beyond the rear end of the sleeve, a retaining ring fitting into said groove and projecting out of the same far enough to engage with the rear end of the sleeve to prevent the withdrawal of the stem in the forward direction, said ring being divided into a plurality of parts having projecting engaging ears, and bolts passing through said ears to fasten the parts

of the ring together and hold them in said groove.

6. In combination, a drawbar having at the front end a cylindrical housing, a coupler stem mounted in said housing so as to be held against lengthwise movement and have capacity for angular movements about its axis, a tongue projecting forwardly from the drawbar at a point above the 10 housing, a support for the front end of said drawbar having a seat for slidably supporting said tongue, and a spring draft rigging connected to the rear end of said drawbar to permit the drawbar to move in the longitudinal direction.

7. In combination, a drawbar having a cylindrical seat whose axis extends longitudinally, a coupler stem mounted in said seat so as to be held against longitudinal 20 movements and have capacity for angular movements about said axis, a spring-pressed plunger extending vertically in said stem in front of said housing, means on the front end of the stem for supporting a coupler head so as to permit the latter to swing in a vertical plane, and a lever pivotally mounted on said stem in advance of said plunger and having its rear end engaging with said plunger, the front end of said lever being adapted to underlie and support a coupler head.

8. In combination, a drawbar having a cylindrical housing at the front end arranged with its axis extending longitudinal-

ly, a coupler stem mounted in said housing so as to be movable angularly about said axis, means at the front end of the stem for pivotally supporting a coupler head so as to permit the latter to swing in a vertical plane, said stem having therein 35 in rear of the aforesaid means a chamber open at the bottom, a spring-pressed vertical plunger in said chamber adapted to be moved into and out of the same through the open bottom of the latter, a cover for 40 said open bottom having an opening through which the lower end of the plunger projects, and a lever pivotally mounted on the stem in front of said plunger and having its rear end in engagement with said plunger, the front end of the lever being adapted to underlie and support a coupler head 45 pivoted to the stem.

9. In combination, a drawbar yieldingly supported at its rear end to permit it to 50 move bodily in the longitudinal direction and swing about a vertical axis adjacent to the rear end, means for supporting the front end of the drawbar so as to permit it to swing in a horizontal plane about said vertical axis, and means for supporting a coupler head upon the front end of the drawbar so as to permit the head to oscillate 55 about a horizontal longitudinal axis and about a horizontal transverse axis.

In testimony whereof, I sign this specification.

HERBERT E. VAN DORN.
